Primary Examiner — Zenia I Bennett

CLAIM

The ornamental design for a surf board, as shown and described.

DESCRIPTION

FIG. 1 is a front, top, right perspective view of a surf board, showing the claimed design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The dashed broken lines in the drawing depict portions of the surf board that form no part of the claimed design.
